CLAIM

The ornamental design for a shelving apparatus, as shown and described.

DESCRIPTION

FIG. 1 is a top, front, left perspective view of a shelving apparatus in an open configuration showing my new design; FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom view thereof; and,

FIG. 8 is a bottom, rear, right perspective view thereof.

The broken lines immediately adjacent to the shaded area define the bounds of the claimed design and form no part thereof. The broken lines depicting the remainder of the shelving apparatus show features that form no part of the claimed design. The break lines shown in FIGS. 1-8 are not part of the claimed design and represent that no particular length is claimed.
